UNITED STATES PATENT OFFICE.

JOSIAH LETCHWORTH, OF BUFFALO, NEW YORK.

DESIGN FOR COCKEYE.

Specification forming part of Design No. 6,151, dated September 24, 1872.

To all whom it may concern:

Be it known that I, JOSIAH LETCHWORTH, of the city of Buffalo, in the county of Erie and State of New York, have invented or produced a new and original Design for Cockeye for Harness, of which the following is a specification:

My design consists of the peculiar construction and arrangement of the loop of the cockeye and the cross-bar with which it connects.

In the accompanying drawing, Figure I is an elevation of a cockeye made after my new design. Fig. II is an elevation at right angles to Fig. I; and Fig. III is a vertical section in line $x\ x$, Fig. I.

Like letters of reference designate like parts in each of the figures.

A represents the loop of the cockeye, which engages with the whiffle-tree. It is egg-shaped or oval, being composed of an outer semicircular portion and an inner elliptical portion, terminating nearly in a point. The outer portion of the metal of the loop A is enlarged and slightly oblong in cross-section at its apex, whence the thickness of the metal gradually diminishes toward the flat cross-bar B. The

sides of the loop A are so connected with the latter that the opening of the cockeye begins directly at the cross-bar B, leaving no intervening neck or connecting shank between the loop and the cross-bar, as heretofore constructed, thereby rendering the cockeye more compact and neater in appearance. The cross-bar B is flat, and corresponds in thickness with the ends of the loop A. Its inner edge is made slightly convex, while its outer edge is beveled off on both sides so as to present a ridge, as clearly shown at b in Figs. II and III. At the apex of the elliptical or inner part of the loop A the cross-bar is beveled off in a similar manner, as shown at c. The ends of the cross-bar B are turned at right angles to the main portion and terminate in flat disks which receive the bolt to which the tug or trace is secured.

I claim as my invention—

The design of the loop A and cross-bar B of cockeye, as herein shown and described.

JOSIAH LETCHWORTH.
